US00D646841S

(12) **United States Design Patent**
Román

(10) **Patent No.:** **US D646,841 S**
(45) **Date of Patent:** **** Oct. 11, 2011**

(54) **HAND PIGMENT APPLICATOR**

(76) Inventor: **Kendyl A. Román**, Sunnyvale, CA (US)

(**) Term: **14 Years**

(21) Appl. No.: **29/389,452**

(22) Filed: **Apr. 12, 2011**

Related U.S. Application Data

(60) Continuation-in-part of application No. 29/310,844, filed on Sep. 12, 2008, now Pat. No. Des. 613,453, and a division of application No. 29/348,937, filed on Feb. 23, 2010, now Pat. No. Des. 638,576.

(57) **CLAIM**

The ornamental design for a hand pigment applicator, as shown and described.

DESCRIPTION

Related applications include:

U.S. Utility patent application Ser. No. 12/381,596

U.S. Utility patent application Ser. No. 12/381,630

U.S. Design patent application Ser. No. 29/348,935

FIG. 1 is a perspective view of the left hand pigment applicator showing my new design;

FIG. 2 is a front elevational view;

FIG. 3 is a rear elevational view;

FIG. 4 is a top elevational view;

FIG. 5 is a bottom elevational view;

FIG. 6 is a left side elevational view;

FIG. 7 is a right side elevational view.

FIG. 8 is a perspective view of a second embodiment of the right hand pigment applicator, which is a mirror image of the left hand pigment applicator;

FIG. 9 is a front elevational view;

FIG. 10 is a rear elevational view;

FIG. 11 is a top elevational view;

FIG. 12 is a bottom elevational view;

FIG. 13 is a left side elevational view; and,

FIG. 14 is a right side elevational view.
